UNITED STATES PATENT OFFICE.

HORACE ERVIEN, OF OGONTZ, PENNSYLVANIA.

CURTAIN-SUPPORT.

1,120,609.

Specification of Letters Patent.

Patented Dec. 8, 1914.

Application filed November 22, 1913. Serial No. 802,437.

To all whom it may concern:

Be it known that I, HORACE ERVIEN, a citizen of the United States, residing in Ogontz, county of Montgomery, State of Pennsylvania, have invented certain Improvements in Curtain-Supports; of which the following is a specification.

My invention relates to certain improvements in the means for supporting the door curtains of an automobile of the touring car type having a top with movable side curtains.

In a prior patent granted to me on the tenth day of December, 1912, No. 1,047,017, I have shown a post for supporting the door curtains made removable from the socket at the free end of the door.

One object of my invention is to arrange the post so that it is not removable, but can be turned and locked in position at the inside of the door.

Another object of the invention is to utilize this post, when located on the side of a door, as a handle therefor.

In the accompanying drawings: Figure 1 is a side view of sufficient of an automobile of the touring type to illustrate my invention; Fig. 2 is a sectional plan view on the line *a—a*; Fig. 1; Fig. 3 is a perspective view of a door showing the post in the upright position; Fig. 4 is a similar view of the door, showing the post located on the inside thereof and in position to be used as a handle; Fig. 5 is a view looking from the inside of the door, showing the post in the upright position and locked to the door; Fig. 6 is a sectional plan view, showing the post in a position similar to Fig. 5; Fig. 7 is a plan view, showing the post shifted to the inside of the door and ready to be turned down to the position shown in Fig. 4; Figs. 8 and 9 are perspective views illustrating modifications of the invention in which the bearing is located on top of the door; Fig. 10 is a view illustrating another modification illustrating the post in an upright position; Fig. 11 is a rear view of the door showing the modification illustrated in Fig. 10, with the post at the back of the door; Fig. 12 is a sectional view on the line *b—b*. Fig. 1; and Fig. 13 is a view illustrating the post made in two parts hinged together.

Referring to the drawings, 1 is the body of an automobile, of any suitable type, and 2 is the door. This door, in the present instance, is hinged at the forward end at 3, 3, but it will be understood that the door may be hinged at the rear without departing from the essential features of the invention. The door may be of any suitable type according to the style of the automobile.

4 is the touring car top, which can be arranged to fold in the ordinary manner, or a fixed open top may be substituted, as desired. The top, in the present instance, is supported by the ordinary bows 5.

6 is the rear curtain.

7 is the forward curtain and 8 is the curtain directly above the door 2. This door curtain 8 moves out with the door when the door is opened. In the present instance, the door curtain 8 underlaps the forward curtain 7 and overlaps the rear curtain 6. The curtain has a flexible metallic band at its upper end, as at 9, and a socket 10 for the reception of the end of a vertical post 11 and is secured to the depending portion of the top 4 at 12. The curtain has a socket 13 at its free end for the reception of the post 11, but this construction may be modified without departing from the spirit of the invention. The curtain is secured to the door by fastenings 14, as shown, so that when the door is opened, as above noted, the curtain is carried with it, giving sufficient head room for a person to enter or leave the car.

My invention relates to the means for mounting the post on the door and the devices above described may be modified without departing from the essential features of the invention.

The post 11 is bent at the lower end, as shown at 15, and has a screw threaded portion 16 which enters a rotating hub 17 in a bearing 18 located at the inner side of the door near the upper edge and is arranged to travel in a slot 19 in the bearing. The ends of the slot form stops to limit the movement of the post in either direction. In the bottom of the bearing 18 is a socket 20 to receive the end 21 of the screw threaded portion 16 of the post so that when the post is raised and turned into position to

properly support the curtain, the end 21 of the post enters the socket 20 and locks the post in its vertical position to the bearing, but as soon as the post is turned to the rear of the door, then the end 21 is withdrawn from the socket and the post is free to be turned down to the position illustrated in Fig. 4, and the end of the post engages a clamp 22, of any suitable type, which holds the post rigidly in its lower position.

10 The post, as shown by dotted lines, Fig. 2, projects from the inner side of the door a sufficient distance to act as a handle for opening and closing the door. It may also be used as a bar for supporting articles carried in the automobile, if desired. The post may be of any length according to the height of the top and, consequently, may be arranged at any angle in respect to the door when in the lowered position.

15 It will be noticed, upon referring to Fig. 7, that the portion 23 of the post is flat and the slot 19 is slightly tapered so that when the post is lowered it is prevented from turning in the bearing.

20 In some instances, the post may be made in two sections hinged together, as in Fig. 13, where it is of such a length that it cannot be located back of the door, but in the majority of cases the post will be of such length that it can rest in a diagonal position, as shown in Fig. 4.

25 In Figs. 8 and 9, I have shown the bearings 18^a located at the top of the door 2^a instead of at the side and the post 11^a has a stem mounted in a swivel hub having a vertical axis, which can be turned freely in the bearing.

30 In Figs. 10 and 11, I have illustrated another form of post 11^b having a stem extending through a hub 17^b swiveled in the bearing plate 18^b. The stem forms a bolt which is actuated by a spring and engages a socket 20^b in the bearing. When the post is in the elevated position, as shown in Fig. 10, a cam on the end of the hub 17^b engages the post 11^b and lifts it when the post is turned so that it can be turned down to the position illustrated in Fig. 11, the projection of the bearing acting as a stop for the post.

35 It will be seen by the above construction that I am enabled to make a post for supporting the door curtains of an automobile which need not be removed from the door when the curtains are dispensed with and which can be turned and located at the back of the door, forming a handle therefor, although, in some instances, the post may fit tightly against the door, being hidden by any suitable flap secured thereto, if desired.

40 I claim:

1. The combination of a vehicle body; a door hinged thereto; a bearing secured to the inner side of the upper portion of the door; a post mounted in the bearing so as

45 to turn therein in a plane substantially parallel with the side of the door in order that the post may be moved to a vertical position to carry a curtain or may be lowered to rest on the inside of the door below the upper edge thereof.

50 2. The combination of a vehicle body; a door hinged thereto and arranged to swing outward; a curtain supporting post pivoted to swing upon an axis which is transverse of the door, said post being on the inside of the door at the upper portion thereof and adapted to be turned into an upright position to support a curtain, or to be turned to another position at the inner side of the door.

55 3. The combination of a vehicle body; a door hinged thereto; a bearing at the upper, outer edge of the door; a hub mounted in the bearing; a post having a curved and a straight portion swiveled in the hub so that, when the post is raised to a vertical position, it will project over the side of the door and will be in position to support the curtain carried by the door and, when turned 90 and lowered, will be in position below the upper edge of the door.

60 4. The combination in a vehicle door, of a bearing thereon having a slot therein; a hub mounted to turn in the bearing; a post bent at one end and located so as to swivel in the hub so that the post can be turned either into the upright position or into a position below the edge of the door.

65 5. The combination in a vehicle door, of a bearing at the outer edge thereof and near the upper end; a post pivotally mounted in the bearing so that it can be turned either into a vertical position at the edge of the door or at an inclined position on the inner side of the door; with means for clamping the post in the inclined position so that it will be rigid with the door and will act as a handle therefor.

70 6. The combination in a vehicle door, of a bearing mounted on the free end of the door having a slot therein; a hub mounted in the bearing; a threaded transverse opening in the hub; a post having a threaded projecting portion adapted to the threaded opening in the post and arranged to travel in the slot in the bearing, the bearing having a socket for the reception of the end of the post when the post is in the upright position, and, when the post is turned and lowered, the post will be withdrawn from the socket.

75 7. The combination of a vehicle door; a bearing on the inner side of the door directly below the upper edge, said bearing having a slot; a hub mounted in the bearing having a threaded transverse opening; a post for supporting the door curtain and having a threaded portion arranged to enter the threaded opening in the hub, said bear-

ing having a socket therein to receive the end of the post when the post is in the upright position, the post having a flattened portion bearing against the wall of the slot 5 when the post is lowered, so as to prevent the post from turning when it acts as a handle for the door.

In testimony whereof, I have signed my name to this specification, in the presence of two subscribing witnesses.

HORACE ERVIEN.
